UNITED STATES PATENT OFFICE.

EDWARD POOLE, OF PHILADELPHIA, PENNSYLVANIA, ASSIGNOR TO THE IVINS, DIETZ & METZGER COMPANY, OF SAME PLACE.

DESIGN FOR CARPET.

SPECIFICATION forming part of Design No. 25,682, dated June 23, 1896.

Application filed May 22, 1896. Serial No. 592,687. Term of patent 3½ years.

To all whom it may concern:

Be it known that I, EDWARD POOLE, a subject of the Queen of Great Britain, residing at Philadelphia, county of Philadelphia, and 5 State of Pennsylvania, have invented and produced a new and original Design for Carpet Fabrics, of which the following is a full, clear, and exact description, reference being had to the accompanying drawing, which 10 forms a part of this specification.

My design, as shown in the drawing, consists in a new design for the body and border of a carpet fabric.

In the drawing, A represents the body, and 15 B the border. The body consists of light and dark ground interspersed as shown, and the figures shown in the drawing extending around the juncture of light and dark ground,

and within said light and dark ground. The border has different ground shades with figure effects, as shown in each. 20

Having now fully described my invention, what I claim, and desire to secure by Letters Patent, is—

1. In a design for a carpet fabric, the body 25 A substantially as shown.
2. In a design for a carpet fabric, the border B substantially as shown.
3. The design for a carpet fabric comprising the body A and the border B. 30

In testimony of which invention I have hereunto set my hand.

EDWARD POOLE.
